FREDERICK B. WALTER, OF WABASH, INDIANA

REFECTORY TABLE

Application filed March 19, 1930. Serial No. 436,943.

The object of my invention is to produce an improved extension leaf structure for tables of the refectory type.

The accompanying drawings illustrate my invention.

Fig. 1 is a plan of a table embodying my invention with portions of a fixed top leaf broken away;

Fig. 2 is a transverse section on line 2—2 of Fig. 1 showing an extension leaf in fully extended position preparatory to either projection to storage position or to service position;

Fig. 3 is a section on line 2—2 of Fig. 1 with an extension leaf in an intermediate position;

Fig. 4 is a section on line 2—2 of Fig. 1 with an extension leaf in service position;

Fig. 5 is a section on line 2—2 of Fig. 1 with an extension leaf in storage position, and

Fig. 6 is a fragmentary section on line 6—6 of Fig. 1.

In the drawings 10, 10 indicate the side boards and 11, 11 the ends boards and 12, 12 the legs of the main frame of the table, the side boards 10, 10 being provided on their upper edges at their middles with upward extensions 10', 10' having a vertical height slightly greater than the thickness of the extension leaves and of such length as to provide storage pockets 13 for the extension leaves below the ends of the main fixed top 14 which is attached to the upper edges of extensions 10'.

Each extension leaf 15 is supported upon the outer ends of two slide bars 16, 16, each of which slides in notch 17 cut in the upper edge of the adjacent end board 11.

The inner ends of two opposite slide bars 16 lie slidably supported in a U-bracket 18 secured the under face of top 14.

Arranged between each opposite pair of slide bars 16 and extending between the inner faces of end bars 11 of the main frame, is a cross bar 20 notched at its upper outer corners, at 21, to correspond with pockets 13. Secured to the bottom face of each notch 17 and forming a slide support for one of the slide bars 16 is a wear plate 25. Each slide

bar 16 at its outer end is recessed on the vertical face adjacent bar 20, at 26 and mounted in each recess is a finger plate 27 provided at its inner end with a finger 28 adapted to coact, when the extension leaf is in service position with a plate 29 secured to bar 20 and having its one end projecting into the recess 26 of the adjacent slide bar 16.

The inner end of each slide bar 16 is reduced in its vertical dimension, as indicated at 30 and the vertical face of said end, adjacent bar 20, is notched at 31 to receive a plate 32, having a cam edge 33 adapted to coact with the horizontal bar of the U-bracket 18, and a slide-limiting upper corner 34, said plates adapted to have interlocking relationships with the downwardly projecting fingers 35 and 36 of a slide-limiting element 37 attached to the under face of a block 38 secured to the under face of top 14 within bracket 18 and adjacent bar 20.

When an extension leaf is in storage position it lies beneath the adjacent end of the fixed leaf 14 and its slide bar 16 rests upon the horizontal bar of bracket 18 and upon plate 25. When the extension leaf is pulled outwardly to the position shown in Fig. 2 the cam edge 33 of plate 32 engages the horizontal arm of bracket 18 and raises the inner end of the slide, the catch point 34 of plate 32 clearing projection 35 of element 37 and coming into engagement with projection 36 of element 37 so as to prevent further outward movement; the parts arriving at the positions indicated in Fig. 2, where the inner edge of leaf 15 is positioned a short distance beyond the outer end of top 14. The leaf 15 is then raised and projected inwardly to bring finger 28 into engagement with the upper face of plate 29, thus holding leaf 15 level with top 14.

In this position the extension leaf structure pivots on the two fingers 28, due to the weight of the leaf 15 and brings the upper corner 34 of plate 32 in behind projection 35 of element 37, thus locking the extension leaf against outward displacement.

In order to facilitate a proper adjustment of the parts plate 27 is most conveniently secured in recess 26 in the following manner:

At an intermediate point plate 27 is perforated at 40 to receive a screw 41. At 42 it is slotted to receive a screw 43; and at 44 it is perforated to receive a screw 45. Plate 27 5 is approximately located by screw 41. Screw 43 is then placed at an intermediate point in the length of slot 42 so as to frictionally retain plate 27 in adjusted position, and the plate is carefully adjusted about the screw 10 41 as a center so that finger 28 will nicely cooperate with the upper face of plate 29. Screw 45 is then driven through perforation 44 to hold plate 27 in final position.

To return a leaf to storage position its outer edge is lifted so as to pivot the leaf structure upon fingers 28 until the upper corner 34, of plate 32 is moved below finger 35 of element 37. The leaf structure is then drawn outwardly to the position shown in Fig. 2 and 20 the leaf allowed to drop, whereupon it may be projected inwardly to the position shown in Fig. 5.

It will of course be understood that the extension leaves may be arranged either at 25 one or both ends of the table or at one or both sides of the table.

I claim as my invention:

1. In a refectory table, the combination with the main frame and main top associated 30 with said main frame to provide a space for an extension-leaf beneath one edge of the main top, of an extension leaf slide structure slidably mounted in the main frame beneath the main top, slidably-coacting elements carried respectively by the main frame and leaf-structure producing positive upward movement of the inner end of the slide-structure by outward sliding of the slide-structure, and vertically-separable elements carried 35 respectively by the main frame and the inner end of the slide-structure of the limiting outward movement of the slide-structure only when the inner end of said slide-structure is elevated.

45 2. A refectory table of the character specified in the immediately preceding claim wherein the two slide-limiting elements are so formed and related that the slide-limiting element carried by the slide structure has two 50 slide-limiting coactive relations with the slide-limiting element carried by the main frame.

3. In a refectory table, the combination with the main frame and main top associated 55 with said main frame to provide a space for an extension-leaf beneath one edge of the main top, of an extension-leaf structure slidably mounted in the main frame beneath the main top, slidably-coacting elements carried 60 respectively by the main frame and leaf-structure respectively producing positive upward movement of the element carried by the slide-structure by outward sliding movement of the slide-structure, and a stop carried by 65 the main top in position to engage the element

carried by the slide-structure when said element is in an extreme vertical position.

4. A refectory table of the character specified in the immediately-preceding claim wherein the two slide-limiting elements are so 70 formed and related that the slide-limiting element carried by the slide-structure has two slide-limiting coactive relations with the stop carried by the main top.

5. In a refectory table, the combination with the main frame and main top associated with the main frame to provide a space for an extension-leaf beneath one edge of the main top, of an extension-leaf structure comprising an extension-leaf and a supporting slide-bar slidably mounted in the main frame beneath the main top, a supporting finger carried by said slide-bar, a plate, carried by the main frame, beneath and over which said finger may be traversed by sliding movement of said bar, a plate carried by the inner end of the slide bar and having a cam-portion and a slide-limiting portion, an element carried by the main top in position to be engaged by said cam portion to produce vertical movement 80 of the inner end of the slide-bar by sliding movement of said slide-bar, and a slide-limiting element carried by the main top in position to be engaged by the slide-limiting portion of the plate carried by the slide-bar when said slide bar is in one extreme of its cam-produced vertical movement.

6. A refectory table of the character specified in the immediately preceding claim wherein the two slide-limiting elements are so formed and related that the slide-limiting elements carried by the main top and slide bar respectively have two slide-limiting relations in similar vertical positions of the inner end of the slide bar.

7. In a refectory table, the combination with a main frame and main top associated with said main frame to provide a space for an extension-leaf beneath one edge of the main top, of an extension-leaf structure comprising an extension-leaf and a supporting slide-bar slidably mounted in the main frame beneath the main top, a supporting finger carried by said slide-bar, a plate, carried by the main frame, beneath and over which said finger may be traversed by sliding movement of the slide-bar, a bracket carried by the under face of the main top and forming a supporting guide for the inner end of the slide-bar, a cam carried by the inner end of the slide bar for engagement with the bracket to produce vertical movement of the inner end of the slide bar when said slide bar is near its projected limit, and slide-limiting elements associated with the bracket and slide-bar respectively to limit projecting movement of the slide bar when the inner end of the slide-bar has been cam-displaced to one vertical limit.

8. A refectory table of the character speci- 130

fied in the immediately preceding claim wherein the two slide-limiting elements are so formed and related that the slide bar has a straight lower edge and a vertical dimension 5 in that region traversing the bracket less than the vertically-unobstructed opening through the bracket.

9. In a refectory table, the combination with a main frame and a main top associated 10 with said main frame to provide a space for an extension-leaf beneath one edge of the main top, of an extension-leaf structure comprising an extension leaf and a supporting slide-bar having a straight lower edge and 15 slidably mounted in the main frame beneath the main top, a fixed support for the inner end of the slide-bar, a supporting finger carried by the slide-bar in such position relative to the weight of the extension-leaf structure 20 that leaf-end weight of the structure beyond the free end of the finger is the greater, a plate, carried by the main frame, beneath and over which the free end of the said finger may be traversed by sliding movement of said 25 bar, and slide-stopping elements carried respectively by the main frame and slide-bar, so arranged as to coact to prevent outward sliding of the bar when the inner end of the bar is elevated by the unbalanced weight of 30 the leaf-end of the leaf-structure.

In witness whereof, I have hereunto set my hand at Wabash, Indiana, this 15th day of March, A. D. one thousand nine hundred and thirty.
